BURIAL CASE

Men Smyser, Cincinnati, Ohio

Application April 10, 1933. Serial No. 665,354

3 Claims. (Cl. 27—5)

This invention relates to improvements in burial cases and primarily to a burial case which will not deteriorate under ground nor collapse under the weight of the earth thereon, and sealed 5 against the invasion of moisture and non-cumbrous so that it can be conveniently handled and conveyed for funeral or interment ceremonies.

An object of the invention is to provide a burial 10 case having the characteristics of a casket or coffin, conveniently transportable and artistic in appearance, and as a vault resisting destruction and collapse under ground, and sealed against the invasion of moisture.

Another object of the invention is to provide 15 a laminated wall burial case consisting of wooden panels exteriorly sheet metal sheathed, the side wall panels on the interior side thereof reinforced with wood boards or planking in truss assembly, 20 and a crowned cover with the arch voussoirs or wooden strips as a unit metal sheathed exteriorly and interiorly with a truss reinforcement on the inner side.

Other features and advantages of the invention 25 will be more fully set forth in a description of the accompanying drawings, in which:

Figure 1 is a side elevation of the improved burial case with a portion of the lid or cover in section.

Figure 2 is a detailed top plan view of the cover 30 with parts broken away to show the structural features thereof.

Figure 3 is a cross sectional view through the cover on line 3—3, Figure 2.

Figure 4 is a central vertical longitudinal section 35 of the receptacle bottom.

Figure 5 is a cross section taken on line 5—5, Figure 4, with the sheet metal sheathing omitted.

Figure 6 is a detailed plan view of a corner of 40 the receptacle with portions shown in section.

Referring to the drawings, the burial case consists of a box or receptacle 1 and a cover 2, each having walls of composite structure as of wood exteriorly metal covered. The end and side walls 45 of the receptacle 1 each comprise a wood panel 3, preferably of cypress, reinforced on the inner side with longitudinal and vertical struts 4 assembled in a truss work nailed or otherwise secured to the panel to give the wall the necessary stability 50 against collapse under the weight of the earth when buried for the usual burial depth.

The vertical struts rest upon a sill 5 as a marginal reinforcement for the bottom panel 6. The horizontal struts along the upper end of the wall 55 panels 3 are tenoned at their opposite ends into

vertical struts. At the opposite ends of the walls and for the side walls, the horizontal struts are of sectional length and tenon into vertical struts intermediate of the length of the sides. Various designs of reinforcing trussing may be employed 60 to give increased rigidity to the panels without materially increasing the weight of the unit. As a casket, it is desirable to keep the weight thereof as low as possible for convenience in conveyance for the funeral.

The wood material used in the panels and reinforcing struts may be treated with a preservative to avoid decay and rot and its use for the inner side of the casket is advantageous for securing, 65 by tacking or otherwise, the lining and drapery fabrics with which a casket is usually decorated.

The upper end or margin of the truss work extends slightly above the upper edge of the wall panels thereby forming a rabbet for the upper edge of the case and a mating joint for the cover. 75 The exterior side of the wood walls and bottom of the case are covered with sheet metal, preferably of copper, the siding or covering 7 having all of its seams or joints made necessary to properly apply the sheet metal over the walls and bottom 80 which are soldered or welded to absolutely seal the same against the admission of water.

A compressible gasket 8 of lead or other suitable material is interposed between the sheet metal covering and upper edges of the walls and 85 the truss work which forms the rabbet, the gasket strips overlapping the joints thereof at the corners, the gasket accommodating for any irregularities in the meeting surfaces when the lead or cover is applied and provides for making 90 a watertight joint. The corner or angle of the rabbet between the offset plane surfaces of the top edge of the case is recessed or indented into the wood to provide a packing space between the 95 adjoining surfaces of the case and cover for additionally sealing the closure joint.

The exterior of the case is provided with the necessary trimmings as the handles and corner or base moldings 9, the latter preferably of sheet 100 metal soldered or welded to the sheet metal siding or covering which serves to reinforce the corners of the case and ornate the structure.

The body or filler portion of the cover 2 primarily is of wooden slat construction of arch form transversely and semi-arched at its opposite longitudinal ends, consisting of a base or sill frame 10 composed of strips of wood suitably joined together at their ends or corners of the frame, rabbeted on the inner side of the 105

upper half of the frame, the frame representing the abutment for the arch.

The top portion of the cover is crowned or arched, the arch formed of a plurality of web-shaped wooden strips or voussoirs 11 with the sides of the frame serving as the abutments for the arch. The arch is of three-centered or elliptical type, although it may follow various other designs. The opposite longitudinal ends of 10 the cover are correspondingly semi-arched, the strips or voussoirs thereof mitered with the longitudinal strips forming the lateral arch.

The wooden body structure of the cover is sheet metal bound or covered exteriorly and interiorly. The sheet metal exterior covering 12 has its edges flanged inwardly to overlap the lower edge of the abutment frame 10 and secured thereto by braces or screws, the flanging overlapping a flange of a Z-bar or strip 13, the 15 flange recessed into the lower edge of the frame. The bar or strip 13 is secured to and covers the inner lower half of the abutment frame. The inner sheet metal covering 14 is marginally inwardly flanged, the flange overlapping the second flange of the Z-bar or strip 13 and secured 20 or fastened to the underside of a ledge or molding 15 for the upper half of the frame, the ledge strip and Z-bar, with the lower edge of the abutment frame, forming a rabbeted edge for the 25 cover mating with the corresponding rabbeted edge of the case to interlock therewith and provide a sealing joint.

The inner cover is fastened to each of the voussoirs by screws or other fastening means 16 distributed at the definite spacings. A brace strip 17 extends centrally and longitudinally of the crown of the cover and is secured to the inner covering 14 and cross bracing by a plurality of metallic brace strips 18 definitely spaced 20 apart for the length of the longitudinal brace bar. Each brace strap is bent to hook form at its opposite ends and engaged through a slot in the inner covering and against an anchoring strip 19 extending longitudinally on the inner side of 25 the cover.

The wooden ledge, cross strap anchoring and central brace strips furnish supports for applying the lining and drapery fabric as an interior trimming for the cover. Illustration of the trimming, however, is herein omitted.

The structure of the cover is secure against collapse under a pressure and weight considerably in excess of the amount of earth thereon for the usual burying depth and the load or weight of the earth upon the cover will wedge or compress the gasket in the mating joint of the cover and case to a degree insuring and maintaining a moisture and air-tight seal.

A comparatively thin gauge of sheet metal, preferably copper, is employed for the exterior sheathing of both the case and cover, permanently protecting the wooden body structure and seal against the permeation of moisture to the interior of the case. The metal sheathing can be enameled or otherwise surface finished to give it aesthetic value and to increase its durability.

The burial case as a single unit substitutes for the use of separate units of casket and vault, considerably reducing the burial cost in the furnishing of an artistic, non-burdensome casket or coffin and a durable and enduring vault.

Having described my invention, I claim:

1. A burial case, comprising, a box-like receptacle of wooden side, end and bottom panels, the panels forming the side and end walls interiorly reinforced by planking in truss assembly and the reinforcement having a continuous top edge extending above the corresponding edges of the wall panels and therewith forming a rabbeted top edge of the receptacle for a mating connection with the cover, and a sheet metal sheathing exteriorly enclosing the receptacle and the rabbeted top edge thereof.

2. A burial case, comprising, a box-like receptacle of laminated wood side walls, end walls and bottom, the inner layer for each of the side and end walls in truss assembly with the upper edge thereof continuous with and extending above the corresponding edge of the outer layer of the wall and therewith forming a rabbet for a mating connection with a cover, and a sheet metal sheathing exteriorly enclosing said receptacle and extended to cover the rabbeted top edge thereof for making a metal to metal contact with a mating metal edge of a cover.

3. A burial case, comprising, a box-like receptacle of laminated wood side walls, end walls and bottom, the inner layer for each of the side and end walls in truss assembly with the upper edge thereof continuous with and extending above the corresponding edge of the outer layer of the wall and therewith forming a rabbet for a mating connection with a cover, and a sheet metal sheathing exteriorly enclosing said receptacle and extended to cover the rabbeted top edge thereof for making a metal to metal contact with a mating metal edge of a cover, and the rabbeted edges each longitudinally recessed providing an intermediate continuous packing space for making a liquid sealing joint with the cover.

MON SMYSOR. 130
